UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-SWITCH-CONTROLLING APPARATUS.

Application filed April 17, 1928. Serial No. 270,699.

My invention relates to railway switch controlling apparatus, and particularly to apparatus of the type involving a polarized relay controlled by a manually operated pole-changer, which relay in turn causes movements of the switch to normal and reverse positions.

One feature of my present invention is the provision of two neutral relays controlled by the polarized relay, and in turn controlling the switch in such manner that if the position of the switch does not correspond to the position of the polarized relay, the switch will immediately be operated to such corresponding position.

I will describe one form of apparatus embodying my invention, and will then point out the novel features thereof in claims.

The accompanying drawing is a diagrammatic view showing one form of apparatus embodying my invention.

Referring to the drawing, the reference character S designates a railway switch which is actuated by an electric motor M through the medium of mechanism which forms no part of my present invention, and which is indicated by a dash line 16. The motor M is controlled by a normal neutral relay D^N , and a reverse neutral relay D^R , and these neutral relays are in turn controlled by a main relay C which is polarized, that is, responsive to reversals of the polarity of the current with which it is supplied. The main relay C is controlled by a pole-changer A operated by a manual lever L having normal and reverse positions corresponding to the normal and reverse positions of the switch S.

Electric current for the operation of all parts of the apparatus is furnished by a battery B, the terminals of which are connected with line wires N and P, respectively, and these line wires extend from the point at which the lever L is located to the point at which the switch S is located.

Operatively connected with the switch S is a normal contact 2-2^a, which contact is closed when and only when the switch is in the full normal position. The switch also operates a reverse contact 2-2^b, which is closed when and only when the switch is in the full reverse position. The switch operates a third or intermediate contact 3-3^a, which is open in the

full normal and the full reverse positions of the switch, but is closed when the switch is in any intermediate position. When the switch is operated by a switch and lock mechanism of any of the usual types, contact 2-2^a will be closed only when the switch is locked in the normal position, contact 2-2^b will be closed only when the switch is locked in the reverse position, while contact 3-3^a will be open when the switch is locked in either the normal or the reverse position and will be closed when the switch is unlocked as well as when the switch is in any intermediate position.

The operation of the apparatus is as follows: As shown in the drawing, the switch S is in its normal position and lever L is also in its normal position, so that the main relay C is energized in the normal direction. The neutral relays D^N and D^R are both open, for reasons which will appear hereinafter.

When the operator desires to reverse the switch S, he moves the lever L to the reverse position, whereupon the main relay C is supplied with current of reverse polarity, with the result that this relay becomes energized in the reverse direction. The reverse relay D^R then becomes energized, the circuit being from line wire P, through front contact 4 of relay C, polar contact 7 of relay C in the reverse position, normal switch contact 2-2^a, front contact 5 of relay C, contact 6 in the reverse position, back contact 10 of relay D^N , and the winding of relay D^R to line wire N. With relay D^R energized, the switch motor M becomes energized, the circuit being from line wire P, through field winding 15, contact 11 of relay D^R , armature 14, and contact 12 of relay D^R to line wire N. The relative directions of flow of current through the field and armature of the motor M are then such as to cause this motor to move the switch to its reverse position. As soon as the operation of the switch mechanism begins, the normal contact 2-2^a opens and the intermediate contact 3-3^a closes. An auxiliary circuit for relay D^R is then closed, which circuit passes from line wire P, through contact 3-3^a, front contact 5 of relay C, contact 6 in the reverse position, back contact 10 of relay D^N and the winding of relay D^R to line wire N. When the switch reaches its full reverse position, con-

tact 3-3^a opens and relay D^R, therefore, becomes de-energized, with the result that the supply of current to the switch motor M is discontinued.

5 To restore the switch to its normal position, the operator returns lever L to the normal position, with the result that relay C again becomes energized in the normal direction. Normal relay D^N then becomes 10 energized, the circuit being from line wire P, through front contact 4 of relay C, contact 7 in the normal position, reverse switch contact 2-2^b, contact 5 of relay C, contact 6 in the normal position, back contact 15 15 13 of relay D^R, and the winding of relay D^N to line wire N. The circuit for the switch motor M is then from line wire P, through field winding 15, contact 8 of relay D^N, armature 14, and contact 9 of 20 relay D^N to the line wire N. The direction of current through the field winding 15 is the same as before, but the direction in which the current flows through armature 14 has been reversed, so that the motor M is operated in 25 such direction as to restore the switch to its normal position. As soon as the switch mechanism begins to move, the reverse contact 2-2^b opens, and the intermediate contact 3-3^a closes, whereupon, an auxiliary circuit 30 for relay D^N becomes closed, this circuit being from line wire P, through contact 3-3^a, contact 5 of relay C, contact 6 in the normal position, contact 13 of relay D^R and the winding of relay D^N to line wire N. When the 35 switch reaches its full normal position, contact 3-3^a opens, so that relay D^N becomes de-energized, and the parts of the apparatus are then restored to their normal conditions.

I will now assume that relay C is energized in the normal direction and that switch S is accidentally moved away from its normal position. The intermediate switch contact 3-3^a will immediately become closed, so that normal relay D^N will become energized, due to its auxiliary circuit hereinbefore traced, with the result that switch S will immediately be restored to its normal position. Similarly, when relay C is energized in reverse direction, if switch S should be accidentally moved away from its reverse position, the reverse relay D^R will be closed, due to its auxiliary circuit through intermediate contact 3-3^a, with the result that the switch will immediately be restored to its reverse position.

It will be noted that the circuit for relay D^N includes a back contact 13 of relay D^R and that the circuit for relay D^R includes a back contact 10 of relay D^N. These back contacts 60 make it impossible for both relays D^N and D^R to be simultaneously energized.

Although I have herein shown and described only one form of apparatus embodying my invention, it is understood that various changes and modifications may be made 65

therein within the scope of the appended claims without departing from the spirit and scope of my invention.

Having thus described my invention, what I claim is:

1. In combination, a main relay responsive to reversals of the polarity of current supplied thereto, means for supplying said relay with current of normal or reverse polarity, a normal relay and a reverse relay, a railway switch having normal and reverse positions, means for energizing said normal relay when said main relay is energized in normal direction and said switch is in any position except its normal position, means for energizing 80 said reverse relay when said main relay is energized in reverse direction and said switch is in any position except its reverse position, and means for moving said switch to its normal or its reverse position according as said 85 normal or said reverse relay is energized.

2. In combination, a main relay responsive to reversals of the polarity of current supplied thereto, means for supplying said relay with current of normal or reverse polarity, a normal relay and a reverse relay, a railway switch having normal and reverse positions, means for energizing said normal relay when said main relay is energized in normal direction and said switch is in any position except its normal position, means for energizing 90 said reverse relay when said main relay is energized in reverse direction and said switch is in any position except its reverse position, an electric motor for causing movements of 95 said switch, and means for energizing said motor to cause it to move the switch to normal or reverse position according as said normal or said reverse relay is energized.

3. In combination, a main relay responsive to reversals of the polarity of current supplied thereto, means for supplying said relay with current of normal or reverse polarity, a normal relay and a reverse relay, a railway switch having normal and reverse positions, 110 three contacts operated by said switch, the first of which is closed only when the switch is in its normal position and the second of which is closed only when the switch is in its reverse position and the third of which is 115 closed only when the switch is in intermediate positions, means for energizing said normal relay when said main relay is in normal position and either said reverse or said intermediate contact is closed, means for energizing 120 said reverse relay when said main relay is in reverse position and either said normal or said intermediate contact is closed, and means for moving said switch to its normal or its reverse position according as said 125 normal or said reverse relay is energized.

4. In combination, a main relay responsive to reversals of the polarity of current supplied thereto, means for supplying said relay with current of normal or reverse polar- 130

ity, a normal relay and a reverse relay, a railway switch having normal and reverse positions, three contacts operated by said switch, the first of which is closed only when the switch is in its normal position and the second of which is closed only when the switch is in its reverse position and the third of which is closed only when the switch is in intermediate positions, a main circuit for said normal relay including a first normal contact of said main relay and said reverse switch contact as well as a second normal contact of said main relay, an auxiliary circuit for said normal relay including said intermediate switch contact and said second normal contact of the main relay but not the first main relay normal contact or the reverse switch contact, a main circuit for said reverse relay including a first reverse contact of said main relay and said normal switch contact as well as a second reverse contact of the main relay, an auxiliary circuit for said reverse relay including said intermediate switch contact and said second reverse contact of the main relay but not the first main

relay reverse contact or the normal switch contact, and means for moving said switch to its normal or its reverse position according as said normal or said reverse relay is energized.

5. In combination, a main relay responsive to reversals of the polarity of current supplied thereto, means for supplying said relay with current of normal or reverse polarity, a normal relay and a reverse relay, a railway switch having normal and reverse positions, means for energizing said normal relay when said main relay is energized in normal direction and said switch is in any position except its normal position, means for energizing said reverse relay when said main relay is energized in reverse direction and said switch is in any position except its reverse position, means for preventing said normal and reverse relays from being energized simultaneously, and means for moving said switch to its normal or its reverse position according as said normal or said reverse relay is energized.

10 15 20 25 30 35 40 45

In testimony whereof I affix my signature.

LESTER E. SPRAY.
